A. W. GATES

DISPENSING DEVICE

Filed Nov. 29, 1921

UNITED STATES PATENT OFFICE.

ALBERT W. GATES, OF PORTLAND, OREGON.

DISPENSING DEVICE.

Application filed November 29, 1921. Serial No. 518,604.

To all whom it may concern:

Be it known that I, ALBERT W. GATES, a citizen of the United States, residing at Portland, county of Multnomah, State of Oregon, have invented certain new and useful Improvements in Dispensing Devices, of which the following is a specification.

My device relates to purveying devices in general, and particularly to such devices as are adaptable for use upon the dining table for the measuring and dispensing of such commodities as sugar, and the like, the object being to provide in such a device simple, easily removable and cleansable means of measuring a predetermined quantity of the commodity and dispensing the same to the operator of the device. A further object of my device is to provide means of mounting advertising matter upon such a device, for use in public eating places.

I accomplish the above objects by means of the construction illustrated in the accompanying drawing, which is a part of this application for Letters Patent, like characters of reference indicating like parts throughout the several views, and in which:

Fig. 1 is an elevation of my device, parts being broken away to illustrate the construction.

Fig. 2 is a fragmentary sectional elevation in dispensing position.

Fig. 3 is a fragmentary sectional elevation in upright position.

Fig. 4 is a sectional plan view upon the line 4—4 in Fig. 1.

Fig. 5 is a perspective view of the cut-off member.

In general my device consists of a receptacle of any suitable form having a hollow base, a dispensing orifice in said base communicating with a dispensing tube, and a removable cut-off member mounted within said hollow base.

The body 6 of the receptacle may be of any suitable and desirable form, and is provided with a hollow cylindrical base 7, said base having an orifice therein communicating with a dispensing tube 8.

At the upper end of the base 7, where it joins the body 6 is disposed the cut-off member. Said measuring member consists of a cylindrical rim 9 projecting downward from a top disk 10, said disk projecting beyond the outer surface of said rim to form an edge to contact with the bottom of the body 6 and thus support the measuring member in

place, as shown in Fig. 1. The disk 10 contains a substantially semicircular orifice 11 therethrough, one edge of said orifice being straight and disposed adjacent to but not exactly upon the diametrical line of said disk. A substantially semicircular diaphragm 12 is disposed beneath the disk 10 and is integrally joined to the rim 9, as shown in Fig. 1. One edge of said diaphragm is straight, and is disposed upon the opposite side of the diametrical line of the disk 10 relatively to the straight side of the orifice 11. A handle 13 is provided upon the cut-off member for convenience in removing the latter.

When the device is in upright position as illustrated in Fig. 1, the commodity therein will substantially fill the cut-off member and the hollow base, as shown in Fig. 3.

When the device is inclined, as shown in Fig. 2, the commodity will flow from the hollow base through the tube 8, the cut-off device preventing any of the commodity other than that contained within the hollow base from escaping.

When the device is again replaced in upright position the commodity will again substantially fill the hollow base, and the device is in condition for further operation.

I am aware that other devices for dispensing measured quantities of commodities such as sugar have been disclosed, but one feature of my device is the removable nature of the cut-off member, which renders the device easily cleanable.

To adopt my device for an advertising novelty, I provide the body with a surrounding skeleton frame 14 separated from the surface of the body 6 by strips 15, and having openings therein through which may be read the contents of advertising cards inserted between said frame and the body of the receptacle.

My device may be made of any size, and constructed of any materials deemed convenient and suitable for a device of this character, and while I have illustrated and described a form of construction and arrangement of parts found desirable in materializing my invention, I wish to include in this application all mechanical equivalents and substitutes that may fairly be considered to come within the scope and purview of my device as defined in the appended claims.

Having disclosed my invention so that others may be enabled to construct and to

use the same, what I claim as new, and desire to secure by Letters Patent is:

A receptacle; a hollow base forming a measuring chamber opening into said receptacle; a cut-off member removably secured in said opening, said cut-off member comprising a disk extending across said opening and having an aperture, a diaphragm beneath said aperture and spaced from said disk and terminating short of the wall opposite to the aperture, thereby forming a baffled passageway between the receptacle and the

measuring chamber; and a discharge outlet on said measuring chamber.

In witness whereof I claim the foregoing 15 as my own I hereunto affix my signature in the presence of two witnesses at Portland, county of Multnomah, State of Oregon, this 15th day of Nov., 1921.

ALBERT W. GATES.

Witnesses:

C. F. BLAKE,
L. J. ROBINSON.
